UNITED STATES PATENT OFFICE.

WILLIAM A. DRAVES, OF MILWAUKEE, WISCONSIN.

DRIVE-CHAIN.

SPECIFICATION forming part of Letters Patent No. 317,103, dated May 5, 1885.

Application filed October 15, 1884. (Model.)

To all whom it may concern:

Be it known that I, WILLIAM A. DRAVES, of Milwaukee, in the county of Milwaukee, and in the State of Wisconsin, have invented certain new and useful Improvements in Drive-Chains; and I do hereby declare that the following is a full, clear, and exact description thereof.

My invention relates to improvements in drive-chains for sprocket-wheels; and it consists in certain peculiarities of construction, as will be fully described hereinafter.

In the drawings, Figure 1 is a perspective view of drive-chain links embodying my invention. Fig. 2 is a sectional view of the same in side elevation. Fig. 3 is a side view showing the links in position for coupling or uncoupling, and Fig. 4 represents a series of links in position around a wheel-segment.

A A are the links of my improved chain, and these are made, as usual, of rectangular form and slightly longer than they are broad. The side bars, a a' , consist of straight rods somewhat curved down at their extreme ends, and the end bars, a^2 a^3 , are connected to these curved ends so as to lie in a slightly-lower horizontal plane than the side bars, a a' . The lower edge of the end bar a^2 is extended down and out opposite the open space between the side bars, and this extended portion is curved upward and toward the upper edge of the said bar a^2 to form the hook a^4 , wherein the bar a^3 of the next link is received and held so that it and the bar a^3 of the first link come in a horizontal plane slightly below the horizontal plane of the side bars, a a' . The upper edges of the side bars, a a' , are cut out on a bevel, as at a^5 a^6 , and the bar a^2 is correspondingly beveled, as at a^7 . The bevel a^6 at the opposite ends of the side bars is at a slightly less obtuse angle than at a^5 , and does not extend beyond the upper edge of the end bar a^3 . This latter is cylindrical, and the ends of the side bars, a a' , connected to it are rounded out beyond the bevel a^6 , so as to conform to the diameter of the said bar a^3 . On the side of the link on which the coupling and uncoupling is to be made the rounding at the end of the bar a is extended backward up to the straight

lower edge of the said bar, as at a^8 . This arrangement will allow for the passage or insertion of the end bar a^3 into the hooking end bar a^2 of the next link; but on the opposite side of the link the rounding of the bar a' is not thus extended backward, but is curved up, as at a^9 , thus forming a stop, against which the end of hook a^4 impinges when the ends of the links are in a suitable position for working, as shown in Fig. 1. This is the only position in which the chain is flexible. The end bar a^3 cannot be inserted too far through the hook because of the stop a^9 , and if not inserted far enough the bevel a^6 meets the bevel a^9 and prevents the links from turning. In order to give to the cylindrical bar a^3 a wide bearing in the said hooking-bar, so as to prevent the slackening of the chain, the outer edge of the bar a^2 is grooved at a^{10} beyond the bevel a^6 , and the corresponding end of the side bars, a a' , are likewise grooved, as at a^{11} . The bearing thus obtained covers fully one-fifth of the end bar a^2 , and will keep the chain in a perfectly straight lateral line without in the least interfering with its flexibility.

Having thus described my invention, what I claim as new, and desire to secure by Letters Patent, is—

In a link for drive-chains, the combination of the straight side bars, a a' , both of which have their extreme ends curved down and are provided with the bevels a^5 and a^6 , the grooves a^7 , and with the stop a^9 upon one of them, the cylindrical end bar a^3 and the end bar a^2 , having the bevel a^6 and hook a^4 , adapted to slide over the end of bar a^3 of the next similar link in the chain and meet the stop a^9 , thus forming a flexible joint of the two links, in which the end bars of each link are carried in a horizontal plane lower than that of the side bars, substantially as shown and described.

In testimony that I claim the foregoing I have hereunto set my hand, at Milwaukee, in the county of Milwaukee and State of Wisconsin, in the presence of two witnesses.

WILLIAM A. DRAVES.
